UNITED STATES PATENT OFFICE.

WILLIS C. HILL, OF PHILADELPHIA, PENNSYLVANIA.

NEEDLE-THREADER.

1,360,400.

Specification of Letters Patent. Patented Nov. 30, 1920.

Application filed August 20, 1919. Serial No. 318,689.

To all whom it may concern:

Be it known that I, WILLIS C. HILL, a citizen of the United States, residing at Philadelphia, in the county of Philadelphia and State of Pennsylvania, have invented 5 certain new and useful Improvements in Needle-Threaders, of which the following is a specification.

This invention relates to certain new and 10 useful improvements in needle threaders, and the primary object of the invention is to provide a device of this character which is of simple and economical construction so as to accordingly be capable of production 15 at a very low cost and which is also simple and positive in its action so as to enable easy and quick threading of the needle.

The invention is illustrated in the accompanying drawings in which:

20 Figure 1, is a side elevation:

Fig. 2, is an edge elevation:

Fig. 3, is a fragmentary detail perspective view of the threadder point, and

25 Fig. 4, is a similar view of a modified form of threadder point.

In proceeding in accordance with the present invention, a pair of similar oppositely disposed thin metal guide members 1, are employed. These plates are secured at 30 their inner ends, as by rivets 2, on opposite sides of an interposed threadder point 3, the latter being composed of a base 4 and a straight uniform cross sectioned shank 5 formed so as to readily pass through the 35 eye of a needle. The point 3 is formed with a notch 6 forming a hook in which the thread is caught. Each member 1, is formed with a longitudinal slot 7, the slots being in register and being alined with the interposed point 3 and shank 5. The slots form 40 bifurcated outer ends for the guides 1, the said outer ends of the latter being tapered to a point and curved outwardly in diverging relation so as to facilitate the entrance 45 of the needle between the guides.

In Fig. 4 the point is shown provided with a pair of thread abutments or notches forming a pair of hooks located on the respective opposite sides of the point so that regardless of which side of the point the thread is passed along, same will be caught by or in one of the hooks.

In operation, the needle is first passed between the guides 1 with its eye receiving the 55 point 3 and shank 5 whereupon the thread is then passed through the slits 7 to engage

the notch 6 following which the thread being held by the fingers the needle is moved along the point 3 and shank 5 and past the notch 6, which causes the thread to pass through 60 the eye of the needle after which the needle is moved to release the thread from engagement with the device.

If desired a handle 8 may be provided, 65 though this is not essential.

Since the guides 1, are similar and the shank 5 is interposed between same and secured by a common fastening which holds the guides in their operative relation, it will be apparent that the device can be economically produced and assembled. The thread 70 it will also be noted is passed through the slots in a straight line and only for a short distance so as to catch in the notch 6, which provides an easy, simple and quick operation. The guides 1, function in a dual manner, i. e. to guide the thread into the notch of shank 5 and to also guide the needle over the point 3 and shank 5. The guides being 75 formed preferably of spring metal are yielding and embrace the needle therebetween with slight pressure so as to hold the latter in position relative to the device.

What is claimed is:—

1. In a needle threadder, a pair of similar 85 substantially flat and independent spring plates having their outer ends free and tapered in a somewhat V-shape and having alined longitudinal thread-receiving slots extending therethrough, and a thread engaging hook interposed between the plates and acting to space same apart, said thread hook being alined with the slots so that the thread can be moved into and through the slots and engaged with the hook, said slots allowing 90 the thread to be extended through the slots and transversely over the outer faces of the plates, said plates being spaced along their adjacent side edges to allow the needle to be placed between the plates from 95 either side of the latter.

2. In a needle threadder, a pair of similar 105 substantially flat and independent spring plates having their outer ends free and tapered in a somewhat V-shape and having alined longitudinal thread-receiving slots extending therethrough, a thread engaging hook interposed between the plates and acting to space same apart, said thread hook being alined with the slots so that the thread can be moved into and through the slots and engaged with the hook, said slots allowing 110

the thread to be extended through the slots and transversely over the outer faces of the plates, said plates being spaced along their adjacent side edges to allow the needle to be placed between the plates from either side of the latter and fastening means passed through each of the plates and

through the thread hook, each slot forming a pair of points at the outer end of the plate, the points of each plate being curved 10 outwardly and in diverging relation.

In testimony whereof I affix my signature.

WILLIS C. HILL.
